UNITED STATES PATENT OFFICE.

TIMOTHY KRIST, OF CLEVELAND, OHIO.

AUTOMATIC STOP FOR GRAPHOPHONES.

Application filed October 20, 1927. Serial No. 227,489.

This invention relates to sound reproducing machines which use record disks and which are provided with a tone arm carrying the stylus which traverses the record 5 grooves and swings over the record supporting table transversely to the record grooves and the main object of the invention is to provide an automatic stopping or braking device for discontinuing the movement of 10 the machine automatically.

Another object of the invention is to generally improve upon automatic stops of this general character and to provide a stop mechanism which is simple in construction 15 and efficient in operation and which is well adapted for the purpose for which it is designed.

Another object of the invention is to provide an automatic stop mechanism of the 20 character described which is adapted for use on all types and styles of graphophones now in general use regardless of the size of the records or the pitch of the record grooves.

A still further object of the invention is 25 to provide an automatic stop mechanism of the character described which embodies a brake which is adapted to engage with the turntable and which is also provided with means for holding the brake in its ineffective 30 or off position during the time that the reproducer mechanism is traveling over the record and which also is provided with mechanism for releasing the brake when movement of the reproducer is discontinued.

35 Further and more limited objects of the invention will appear as the description proceeds and by reference to the accompanying drawing in which Fig. 1 is a top plan view of the preferred embodiment of my invention attached to the standard graphophone and in which parts are broken away to more clearly illustrate the details of the apparatus; Fig. 2 is a top plan view somewhat similar to Fig. 1 showing the brake in an 40 intermediate position; Fig. 3 is a view similar to Fig. 2 with the brake in the off or ineffective position and Fig. 4 is a detail view in side elevation showing the manner of attaching a part of the mechanism to the tone 45 arm.

Referring now to the drawing, the numeral 1 designates the housing or casing of the graphophone within which is enclosed the mechanism for operating the device. Arranged within the housing is a motor 2 having a shaft 3 projecting upwardly there-

from and having mounted thereon an eccentric or cam 4. The top of the housing 1 forms a base plate or support 5 through which the shaft 3 projects and to which 60 the stop mechanism is secured. Pivotaly mounted on the housing 1 is a tone arm 6 to the outer end of which is pivotally secured a reproducer 6' having a needle 8 thereon adapted to engage and travel over 65 the surface of the record in a manner well known to those skilled in the art. Carried by the tone arm 6 is an arm 7 which is pivotally secured thereto by means of a pin 8 and which is provided with a hinge joint 70 8'. Also carried by the tone arm are a pair of spaced downwardly projecting parallel arms 9 and 10 which serve to move the arm 7 in a manner to be hereinafter more fully described. There is a slight lost motion between the arm 7 and the spaced projections 75 9 and 10 which allows the reproducer to wobble without moving the arm 7, thereby preventing the brake from being released until the record has been played.

80 Pivotaly mounted on the support 5 is an arm 11 which is secured at one end to the support 5 by means of a pin 12. Carried by the opposite end of the arm 11 and rotatable with respect thereto is a member 13 85 which is preferably annular in shape and provided with a pin 14, the purpose of which will hereinafter appear. Also carried by the support 5 is a spring 15 which bears against the arm 11 and urges the same 90 in a counter clockwise direction as seen in Fig. 1. A stop pin 16 carried by the support 5 limits the movement of the arm 11 in this direction. Pivotaly secured to the support 5 adjacent the member 13 is a pawl 95 17 one end of which is V-shaped and projects over the member 13 and other end of which is bent substantially at right angles as shown in Figs. 1, 2 and 3.

100 Carried by the support 5 is a latch 19 which is substantially T-shaped and is pivotally secured thereto by means of a pin 20 and is provided with a portion 21 which projects in close proximity to one end of the pawl 17. The latch 19 is also provided at 105 one end with the projecting catch portion 22, the purpose of which will hereinafter appear. Also carried by the support 5 is a lever 23 which is pivotally secured thereto as shown at 24. The lever 23 is provided at one end with a resilient projecting portion 25 which is disposed in close proximity

to one end of the pawl 17, and is adapted to be engaged thereby in a manner to be hereinafter described. The lever 23 is also provided with a V-shaped extension 26 which projects over the member 13 and is adapted to be engaged by the pin 14 in a manner to be hereinafter set forth. The opposite end of the lever 23 projects under and beyond the arm 7 as shown most clearly in Fig. 1. Disposed on opposite sides of the lever 23 are stop pins 27 and 28 which serve to limit the movement of the same. The lever 23 is also provided with a resilient portion 29 shaped as shown in Fig. 1 which projects in close proximity to the latch 19 and is engaged thereby in a manner to be hereinafter described. Also carried by the support 5 is a brake lever 30 which is pivotally secured thereto by a pin 31 and is normally urged in a clockwise direction by a spring 32, one end of which is secured to a pin 33 and the opposite end of which is secured to the brake lever. Secured to the brake lever 30 is an arm 34 carrying a brake shoe 35 which is adapted to engage with the edge of the turntable in a manner to be hereinafter described.

Also carried by the brake lever 30 is a slightly resilient arm 37 which projects outwardly therefrom at substantially right angles thereto and extends under the arm 7 and lifts and moves the same when the brake lever is moved to the position shown in Figs. 2 and 3. Secured over the shaft 3 and adapted to rotate therewith is a turntable 38 which is adapted to support the usual disk record in a manner well known to those skilled in the art.

When the shaft 3 and cam 4 are rotated, the cam 4 engages with the edge of the member 13 and serves to rotate the same. In the preferred embodiment of my invention, the parts are so proportioned that the ratio of movement of the shaft 3 and member 13 is about 4 to 1. From an inspection of Figs. 1, 2 and 3, it will be seen that one end of the pawl 17 projects over the member 13 and is engaged by the pin 14. The pin 14 also engages the Y-shaped projection 26 and serves to move the arm 23 about its pivot 24. The member 13 is rotated in a counter clockwise direction so that the pin 14 actuates the pawl 17 in advance of the movement of the lever 23.

The arm 7 projects over the support 5 as shown and drags on the projecting end of the lever 23 so that when the reproducer is traveling over the record the drag on the lever 23 serves to move the same in the direction of the arrow in Fig. 1. The pin 14 striking against the Y-shaped member 26 tends to move the arm 23 in the opposite direction. The pins 27 and 28 serve to limit the movement of the lever 23 in each direction. Carried by the support 5 is a cam

member 39 which is disposed in the path of movement of the arm 37 so that when the brake lever 30 is moved from the position shown in Fig. 2 to the position shown in Fig. 3, the arm 37 rides up one side of the cam 39 and down on the other side and moves with it the arm 7, which movement serves to take up the lost motion between arm 7 and the downwardly extending projections 9 and 10. The counter clockwise movement of brake lever 30 performs no useful function as far as taking up the lost motion is concerned. There must be sufficient lost motion to allow for considerable wobbling of the tone arm. Some records give the tone arm very little if any wobble and hence the excess lost motion would have to be taken up, hence the necessity for the arm 37 which takes up the lost motion and permits brake lever 30 to be moved from the position shown in Fig. 2 immediately after the stylus has been placed on the record.

When it is desired to start the machine, the record is first placed on the turntable and the brake lever 30 moved from the position shown in Fig. 1 to the position shown in Fig. 2, thus releasing the turntable which starts to rotate in a clockwise direction, as seen in Fig. 1. The inwardly projecting end of brake lever 30 engages the latch 19 and resilient projection 29 and moves the lever 23 about its pivot to the position shown in Fig. 2. The stylus is then placed upon the record in the usual manner. The brake lever 30 is then moved to the position shown in Fig. 3, in which position the latch 19 is engaged by the depending end of the brake lever 30 and is held thereby. In this position of the lever 30, the arm 37 is off of the cam 39 so that the arm 7 is in engagement with the projecting end of the lever 23. The turning of the shaft 3 and turntable 38 tend to move the reproducer across the record toward the center thereof. As the shaft 3 rotates, the eccentric 4 engages the member 13 and rotates the same. As the member 13 is rotated, the pin 14 engages with the Y-shaped portion of pawl 17 and oscillates the same. Due to the frictional engagement of the arm 7 with the projecting end of the lever 23 the lever 23 will be in the direction of the arrow in Fig. 1 in which position the projecting portion 25 will be so disposed as to be out of the path of movement of the pawl 17. Upon continued movement of the member 13, the pin 14 engages with the Y-shaped projection 26 and moves the lever 23 in the opposite direction whereupon the projected portion 25 is brought to a position to be engaged by the pawl 17 whereupon the pawl 17 will strike the projecting portion 25 and move the same against the end 21 of the latch lever 19 to release the brake lever and allow the spring 32 to move the brake shoe 35 into engagement with the rim of the

turntable. Should it be desired to operate the machine in the usual manner without the automatic stop being effective, the brake lever 30 may be moved to the position shown 5 in Fig. 2 whereupon the mechanism will operate in the usual manner.

It will therefore be seen that as long as the reproducer is traveling over the record, the arm 23 will be oscillated. When the 10 movement of the reproducer over the record is discontinued, the oscillation of the member 23 will also be discontinued and the projecting portion 25 will be moved in a position to be engaged by the pawl 17 (if not already 15 in this position) and upon the next operation of the pawl 17, the latch 19 will be moved to the position shown in Fig. 1, thereby releasing the brake lever 30 and allowing the spring 32 to move the brake 20 shoe 35 into engagement with the edge of the turntable, whereupon the movement of the turntable will be discontinued.

It will therefore be seen that the brake will be held in the off position so long as the 25 arm 7 is being moved across the record and that upon discontinuance of the movement of the reproducer and arm 7, the latch 19 will be actuated to release the brake. It will also be seen that, with the parts in the position shown in Fig. 2, the break lever cannot 30 be released, because of the fact that the projecting portion 25 is so disposed as to be out of the path of movement of the oscillatory pawl 17.

Secured to and preferably forming a part 35 of the lever 7 is a weight 40, the end of which projects downwardly and slides over the support 5 and serves to steady the movement of the arm 7 and to prevent undue oscillation thereof due to the wobbling of the reproducer needle with the grooves of the record.

Various changes may be made in the details of my construction without departing 45 from the spirit of my invention and while I have described the preferred embodiment of my invention, it is obvious that the arm 7, lever arm 23 and brake lever 30 and their associated parts may each be made of a single 50 piece of material, if desired. It is also understood that the mechanism which is carried by the support 5 may, if desired, be secured to a plate which may be secured to the support 5. I therefore wish my invention 55 to be limited in accordance with the scope of the appended claims.

It will now be clear that I have provided an automatic stop mechanism which will accomplish the objects of the invention as 60 hereinbefore stated.

Having thus described my invention, what I claim is:

1. The combination of a graphophone having a turntable adapted to support a record thereon, a shaft by means of which 65

said turntable may be turned, means for rotating said shaft, a reproducer adapted to travel over said turntable and to engage with said record, a brake adapted for engagement with said turntable, mechanism 70 actuated by the movement of said shaft to release said brake and to render the same effective, said mechanism being inoperative when said reproducer is moving over said record, said mechanism including a tone 75 arm, a lever connected with said tone arm so as to provide a lost motion connection therebetween thereby to allow for a wobble of the stylus with the record grooves.

2. The combination of a graphophone 80 having a turntable adapted to support a record thereon, a shaft for turning said turntable, a tone arm, a reproducer connected with said tone arm and adapted to travel over said turntable and to engage with said record, a brake adapted for engagement 85 with said turntable, a latch holding said brake in the inoperative position while the reproducer is traveling over said record and mechanism operated by the movement 90 of said shaft for releasing said latch and rendering said brake effective, said mechanism being operative only when said reproducer is at rest, and including a lever having a lost motion connection with said 95 tone arm whereby to permit a wobble of the reproducer with the grooves of the record without releasing the brake lever.

3. The combination of a graphophone 100 having a support, a shaft projecting through said support, a member rotatably mounted on said support and a driving connection between said member and shaft, a pawl pivotally mounted on said support adjacent 105 said member and adapted to be oscillated thereby, a lever pivotally mounted on said support and having a portion at one end projecting in close proximity to said pawl and adapted to be engaged thereby, a tone 110 arm having an arm thereon projecting over said support and adapted to frictionally engage the opposite end of said lever, said lever also having a portion projecting over said member and adapted to be engaged thereby whereby to move said lever in one 115 direction, said tone arm serving to move said lever in the opposite direction, a brake lever pivotally mounted on said support, a latch pivotally mounted on said support and having a portion adapted to be engaged 120 by the projecting portion of said lever, said latch also having a portion adapted to engage said brake lever to hold the same in the off position, said member being so mounted and constructed as to actuate said 125 pawl in advance of said lever whereby said brake may be released only when the movement of said tone arm is discontinued, a turntable secured over said shaft and actuated thereby and having a portion adapted 130

to be engaged by said brake lever, and means for rotating said shaft.

4. The combination of a graphophone having a support, a shaft extending through said support, a turntable secured over said shaft and actuated thereby, a brake lever mounted on said support and adapted to engage said turntable, spring means normally urging said brake lever to the brake position, a latch pivotally mounted on said support and adapted to engage said brake lever to hold the same in the off position, a tone arm mounted on said graphophone, a reproducer carried by said tone arm and adapted to traverse a record supported on said turntable, a lever arm carried by said tone arm and projecting over said support and operating mechanism associated with said arm, brake lever and shaft for holding said brake lever in the off position while said reproducer is traveling over said record, and a lost motion connection between said lever arm and tone arm for permitting a wobble of the reproducer within the grooves of the record without releasing the brake lever.

5. The combination of a graphophone having a turntable adapted to support a record thereon, a shaft for turning said turntable, a reproducer adapted to travel over said turntable and to engage said record, a brake lever adapted for engagement with said turntable, a latch for holding the brake lever in the off position, and mechanism disposed between said shaft and latch and having a part operatively associated with said reproducer in such a manner that said brake lever will be held in the off position while said reproducer is traveling over said record.

6. The combination of a graphophone having a turntable adapted to support a record thereon, a tone arm supported on said graphophone and having a reproducer secured thereto, a lever secured to said tone arm and projecting beneath said turntable, a brake lever adapted for engagement with said turntable, a latch for holding said brake lever in the off position, and mechanism operatively associated with said latch, lever and turntable for holding said brake lever in the off position while said reproducer is traveling over said record and for releasing said latch and rendering said brake effective when the movement of said reproducer is discontinued, and a lost motion connection between said lever and tone arm whereby to permit a wobble of the reproducer with the grooves of a record without releasing the brake lever.

7. The combination of a graphophone having a turntable adapted to support a record thereon, of a tone arm, a reproducer connected with said tone arm, a lever connected with said tone arm and projecting

beneath said turntable, a brake, a spring tending to set said brake, a latch for holding said brake into the off position, a reciprocatory brake releasing member movable to engage and trip said latch, a member actuated by the movement of said tone arm and operating to shift said brake releasing member out of operative position while the reproducer is traveling over a record, driving connection between the turntable and reciprocatory member and a lost motion connection between said lever and tone arm for permitting a wobble of the reproducer with the record grooves without releasing the brake.

8. The combination of a graphophone having a turntable adapted to support a record thereon, of a tone arm, a reproducer connected with said tone arm, a brake for said turntable, a spring tending to set said brake, a latch for holding said brake in the off position, an oscillatory brake releasing member movable to a position to release said latch, a lever carried by said tone arm and projecting beneath said turntable, an oscillatory member actuated by the movement of said tone arm for preventing said brake being released while the reproducer is traveling over a record, a driving connection for said oscillatory member and a lost motion connection between said lever and tone arm to permit a wobble of the reproducer with the record grooves without releasing said brake.

9. The combination with a graphophone having a turntable adapted to support a record thereon, of a tone arm, a reproducer connected with said tone arm, a lever connected with said tone arm and projecting beneath said turntable, a brake, a spring tending to move said brake to braking position, a latch for holding said brake in the off position, a reciprocatory brake releasing member movable to engage and trip said latch, a member actuated by the movement of said tone arm and operating to move said brake releasing member out of operative position while the reproducer is traveling over a record, a driving connection between said turntable and reciprocatory member and a lost motion connection between said lever and tone arm for permitting a wobble of the reproducer with the record grooves without releasing said brake and means for taking up any excess lost motion, the brake being so positioned with respect to the turntable as to be urged against the turntable by the movement of the turntable.

10. The combination of a graphophone having a turntable adapted to support a record thereon, of a tone arm, a reproducer connected with said tone arm, a lever connected with said tone arm and projecting beneath said turntable, a brake, a spring tending to set said brake, a latch for hold-

ing said brake into the off position, a reciprocatory brake releasing member movable to engage and trip said latch, a member actuated by the movement of said tone arm and operating to shift said brake releasing member out of operative position while the reproducer is traveling over a record, driving connection between the turntable and reciprocating member and a lost motion connection between said lever and tone arm

for permitting a wobble of the reproducer with the record grooves without releasing the brake, said brake lever being pivotally secured to the graphophone in such a position that when the brake is applied there will be a wedging action between the turntable and brake.

In testimony whereof, I hereunto affix my signature.

TIMOTHY KRIST.
